UNITED STATES PATENT OFFICE.

WILLIAM H. GRADY, OF LOUISVILLE, KENTUCKY, ASSIGNOR, BY MESNE ASSIGNMENTS, TO AMERICAN CREEGSOTING COMPANY, A CORPORATION OF DELAWARE.

DUMPING TABLE.

Application filed June 29, 1927. Serial No. 202,312.

This invention relates to dumping tables for use in loading tram cars with railroad ties.

The device is particularly designed for use in loading ties from the piles in the storage yards of wood-preserving plants. In such yards the ties are arranged in piles, from which they are transferred to tram cars arranged to carry loads, which are of such shape that the tram cars with their loads of ties can be pushed into the cylinders in which they are subjected to the preservative treatment. The dumping table, according to this invention, is located on or near a railway track passing between the piles of ties, the tram cars to be loaded being on an adjacent track. A traveling crane on the first track picks up a number of ties which are then deposited on the dumping table, from which they are transferred to the tram cars, on which the load is formed by specially arranged forms and held in place by the usual bails secured to bolster arms on the tram cars. See e. g. Patents No. 1,428,474, No. 1,510,202 and 1,528,041.

The dumping table is particularly designed to facilitate this transfer with a minimum of manual labor. The construction of the dumping table and the manner in which it is used will be readily understood from the accompanying drawings in which:

Fig. 1 is an elevation, parts being shown in section;

Fig. 2 is a plan of Fig. 1;

Fig. 3 is an elevation at right angle to that of Fig. 1, the frames and former device being omitted;

Fig. 4 is a plan of the arrangement for raising and lowering the roller frames; parts being broken away;

Fig. 5 is a side view elevation of Fig. 4; Figs. 6, 7 and 8 show details.

The whole device may be and is preferably mounted on a wheeled truck, so that it may be moved along the track. Supported on these wheels is a strong framework of wood and metal, the details of which are not essential, and will readily be understood from the drawings. Supported on this framework are downwardly inclined skidways 5, 5, here shown as lengths of railroad rails. These skidways slope at any convenient angle, as shown, and the rear ends are turned up to prevent the ties from slipping off the back end. Arranged between the skidways are

frames 21 carrying on upstanding side webs 22 a series of rollers 20. Two such frames are shown in Fig. 2. On the bottom flanges, 23, of the webs, 22, are secured feet, 10, (see Fig. 5) rounded at their lower ends and resting on bearing plates, 11, secured to another beam, 26.

The bearing plates 11, as shown in Fig. 5, have at one end inclined surfaces. When the feet, 10, are in the position shown in Fig. 5, the rolls are below the upper surfaces of the skid rails. When the frames are moved longitudinally, the feet slide up the inclined surface and the upper rims of the rolls extend above the skid rails, as shown in Fig. 2. The frames are moved longitudinally by means of connecting rods 9 connected at one end to the bottom flanges, 23, of webs, 22, and at the other to levers 8 mounted on shafts 8', having handles 7. The shafts 8' are carried in bearings on fixed parts of the table. It will be understood that each side of each frame may be provided with similar raising and lowering devices and that the crank shafts extend beyond each skid rail, so that the frames can be operated from either side. An additional extension apron or frame 12, likewise provided with rollers, is hinged by means of shaft 30 to the end of the skid rails. When not in use, it can be folded back on the table. When in use, it rests on a cross-bar 13, extending across the tops of the posts 4 of the adjacent load-forming device. Elevated walkways 14 are located on each side of the table, as in operation a man is required on either or both sides to feed the ties from the table to the tram cars.

In operation a bundle of ties is gathered from the stacks of ties in the yard by a gathering cable and crane. The bundle of ties is placed on the skids of the dumping table, the roller sections being depressed below the skidways so that this heavy load, which may be five or six tons, does not come directly on the rollers. The ties nearest the delivery end of the table are passed by the workman over the roller apron into the tram car. As the ties are removed from the table, the distance from tram to ties becomes greater and greater, and the roller frames can then be successively raised, to facilitate the movement of the ties from the table to the tram car. The movement is a gravity action and the workman or workmen on either or both

of the walkways merely keeps the ties straight as they pass over the table.

The dumping table may either be mounted on a wheeled truck, as shown in Fig. 1, or 5 metal feet 15, as shown in Figs. 6 and 7.

When mounted on wheels a track clamp such as shown in Fig. 8 may be used. Two diverging clamping pieces 31 engage the head of the rail, and may be loosened or tightened 10 by ring 32. These pieces 31 are supported by a plate 33, fastened as shown in Fig. 3 to the lower beam of the truck. The truck is the more convenient form, but not necessary, as the entire table could be lifted about by 15 the traveling crane.

When the ties are to be taken directly to the treating cylinders, the loads on the tram cars must conform in shape to that of the treating cylinders, the loads being held in 20 shape by bails, as shown in the patents above referred to.

In order to so shape the loads, I use the former device, shown at the right of Figs. 1 and 2, which comprises beams 34, extending 25 beneath the tram car track. Pairs of these beams are located at intervals of about 200 feet along the tram car track. Mounted at each end of these beams are sockets 35 into which fit upright members 4, held in 30 place by bolts. The uprights may be braced by arms 36, engaging by means of bolts the flanges of angle pieces secured to beams 34. Swinging arms 3 are mounted at the upper portion of the uprights 4, and have their 35 inner sides curved to fit the desired configuration of the load on the tram car, 50, diagrammatically shown in outline.

The two members 4, on the side adjacent the dumping table, carry a cross-bar 13 on 40 which rests the extension table 12. When the tram car is loaded it is moved forward away from the formers, the swinging arms 3 of which swing with the direction of the tram movement and offer no resistance. The bails 45 may be placed over the load either before or after the tram is moved from the formers.

When the dumping table and formers are set up at any desired place on the tracks in the storage yard, this point is termed a "loading station," and once the loading equipment 50 is set up, it may not be necessary to move it more frequently than once every one to three days. When a move becomes necessary, the extension 12 is folded back on the main table, 55 the uprights 4 and attached parts may be detached by removing the bolts connecting them to beams 34, and placed on the walkways 14, and the table moved to the next selected station, all of which can be effected in a few 60 minutes.

The use of the combined dumping table and load former results in notable economies in the handling of ties.

I claim:

65 1. A dumping table adapted for handling

railroad ties comprising inclined skidways, means for supporting a series of rollers adjacent the skidways, and means for raising and lowering the supporting means to raise or to depress the rollers above the tops of the skidways, the rollers being mounted in frames, and comprising inclined bearing plates, feet on the frames resting on the bearing plates, and means for moving the frames to and fro to thereby raise and lower the frames. 70 75

2. A dumping table adapted for handling railroad ties comprising inclined skidways, means for supporting a series of rollers adjacent the skidways, means for raising and lowering the supporting means to raise or to depress the rollers above the tops of the skidways, and a pivoted roller carrying frame mounted at the end of the skidways, the said table being mounted on a railway track, of a load-forming device located near an adjoining track, said load-forming device comprising curved arms mounted to swing on upright posts, and a cross-bar on two of said posts for supporting the pivoted roller-carrying frame. 80 85

3. The combination of a portable dumping table adapted for handling railroad ties comprising inclined skidways having means for supporting a series of rollers adjacent the skidways, means for raising and lowering the supporting means to raise or depress the rollers above the tops of the skidways and a pivoted roller-carrying frame mounted at the end of the skidways,—with a portable load-forming device having means for supporting said pivoted roller-carrying frame. 90 95 100

4. The combination of devices as claimed in claim 3, in which the dumping table and load-forming device are mounted on adjacent railway tracks.

5. A portable dumping table including inclined skidways, a plurality of frames movably mounted on said table and spaced longitudinally of said inclined skidways, said frames carrying rollers adjacent said skidways, means for independently raising and lowering each of said frames to thereby project the rollers thereon above said inclined skidways, and an additional roller-carrying frame extensibly connected to said table, said frame being movable to a position beyond the lower ends of said skidways. 105 110 115

6. The combination of a portable dumping table comprising inclined skidways having means for supporting a series of rollers adjacent the skidways, means for raising and lowering the supporting means to raise or depress the rollers above or below the tops of the skidways, with a portable load-forming device, and a roller-carrying frame supported by and adapted to connect the said dumping table and the load-forming device. 120 125

In testimony whereof, I affix my signature.

WILLIAM H. GRADY.
